EDWARD O. KEATOR, OF CINCINNATI, OHIO.

ADJUSTABLE STRUT.

1,198,728.

Specification of Letters Patent. Patented Sept. 19, 1916.

Application filed September 8, 1915. Serial No. 49,631.

To all whom it may concern:

Be it known that I, EDWARD O. KEATOR, a citizen of the United States of America, and resident of Cincinnati, county of Hamilton, State of Ohio, have invented certain new and useful Improvements in Adjustable Struts, of which the following is a specification.

This invention relates to improvements in 10 adjustable struts for supporting temporary form work for concrete construction and has for an object to produce an adjustable strut in which the relatively movable members may be positively adjusted to prevent 15 an initial giving or settling thereof when the load is placed on the strut.

A further object is to produce an adjustable strut in which the grip of its clamps will increase in direct proportion to the load 20 placed on the strut.

These and other objects are attained in the strut illustrated in the accompanying drawings and described in the following specification in which:

25 Figure 1 is a side elevation of a strut embodying my invention. Fig. 2 is a fragmental side elevation upon an enlarged scale of a strut embodying my invention, certain parts being shown in section. Fig. 30 3 is a perspective view upon an enlarged scale of an automatic clamp embodying my invention.

Heretofore in struts of the adjustable type, clamping members have been employed which when set to lock the adjustable members of the strut in their adjusted positions for receiving a load, would nevertheless permit the members of the strut to give or settle to a certain extent before 40 finally supporting the load without further relative movement of the members. This settling is variable in amount and an allowance has to be made therefor in setting up form work, by providing suitable means 45 such as wedges for lifting the form work the amount the members of the strut have settled. In order to overcome this objection to struts heretofore employed I have devised the strut hereinafter described and 50 illustrated in the accompanying drawings which consists of a central support member

4 adapted to rest upon the strut supporting surface, and side support members 5 and 6 located on opposite sides of the central support member and connected at their top 55 ends by means of a block 7, with plates 8 secured thereto intermediate the ends of the side members and embracing the remaining opposite sides of the central support member, the plates preventing displacement 60 of the side support members from the central support member. The lower ends of the side support members are free and are adapted to be pressed against the opposite sides of the central support member to frictionally lock the side support members 65 thereto.

In order to bring the free ends of the side support members into clamping frictional engagement with the central support member I have provided a clamping device 9. This clamping device consists of plates 10 located on each side of the central and side support members and connected at their ends by means of bolts 11 and 12. Bolt 70 11 forms a journal pin for an eccentric clamp 13 the surface of which engages a plate 14 secured to the end of the side support member 5. Member 5 is preferably somewhat longer than support member 6 75 and the bolt 12 is located beneath the end of member 6. This bolt forms a journal pin for an automatic clamp 15 which engages both the side of the central support member 4 and the lower end face of the side support member 6. The upper face 16 of the automatic clamp is provided with slots 17 and 18 through which pass nails which are driven into the end of the side support member 6 for the purpose of preventing 80 displacement of the clamping device 9. The surface 19 which engages the friction surface of the central support member 4 is slightly curved and is provided with a series of serrations or corrugations 19^a extending 85 across the clamp from one end to the opposite end. These corrugations are pressed against the surface of the central support member 4 when the clamping device is secured in its member locking position. The automatic clamp 15 has its journal mounting apertures 20 located in such 90 95 100

a position relatively to the curved surface 19 as to bring its journal nearer the apex 21 formed by the surfaces 16 and 19, than to the opposite end 24 of the curved surface 5 19. This results in the clamp occupying a tilted position as shown in Figs. 1 and 2 when the clamp 13 is caused to exert a pull upon the plates 10 in the direction of their axes for the reason that the journal pin 10 exerts a greater pressure at the edge 21 of the curved surface 19 than at its opposite edge 24, because of the difference in the lengths of lever arms between the journal pin and the edge 21 and between the journal 15 pin and the opposite edge 24 of the curved surface. This results in the clamp assuming a position in which a line of force will extend at right angles to the surface of the central support member 4, which surface 20 forms a tangent to the curve of the surface 19 of the clamp when it occupies this position. The result of this is that the corrugations 19^a will be pressed against the surface of the support member 4 with the upper end 22 of the automatic clamp in engagement with the lower end of the side support member 6.

The clamping device is secured in position by means of the clamp 13 when it is 30 driven into engagement with the plate 14 located on the side support member 5, by hammering upon the surface 23 of the clamp. With the clamping device adjusted as above described to hold the support members of the strut in their adjusted positions, there can be no giving or settling of the members relatively to one another when the load is placed upon the strut, for the reason that downward movement of the members 5 35 and 6 with relation to the central support member will cause the cam shaped surface 19 to press with increasing pressure against the surface of the central support member 4 because of the eccentric location of the journal pin with relation to adjacent points on the surface 19. Furthermore any tendency toward downward motion of the side support member 5 will tend to draw the clamp 13 into closer relation with the plate 14 and 40 thus draw the sides of the side support members 5 and 6 into increasing frictional engagement with the sides of the central support member 4, as well as also drawing the automatic clamp into engagement with the 45 surface of the central support member 4 with its upper end 22 in lifting engagement with the side support member 6.

Having thus described my invention, what I claim is:

60 1. In combination in a strut a central support member, side support members located on opposite sides of the central support member, and a clamping device adapted to

frictionally engage the inner faces of the side support members with opposite faces 65 of the central support member, said clamping device consisting of a clamp adapted to be driven into engagement with the outer face of one of said side support members, a second clamp having an eccentric surface 70 for engaging the opposite side of the central support member and a supporting surface for engaging the end of the other side support member, and means connecting the clamps, embracing the member, and adapted 75 to cause said first mentioned clamp to bring the support surface of the said second mentioned clamp into engagement with the end of the other side support member when the first mentioned clamp is driven into clamp- 80 ing engagement with the first mentioned side support member.

2. A strut comprising central and side support members, and a clamping device adapted to secure the central and side support members in adjusted positions relatively to one another, said clamping device consisting of a clamp engaging one side of 85 one of said side support members, a second clamp having a curved surface adapted to 90 engage said central support member and a flat surface adapted to support one of said side support members, and means connecting the clamps and embracing the members for operating the second mentioned clamp 95 when the first mentioned clamp is operated, whereby the second mentioned clamp will be rocked upon its curved surface to bring its flat surface into supporting engagement with the side support member. 100

3. In an adjustable strut the combination of central and side support members, and a clamping device adapted to frictionally lock the members together, said clamping device comprising a clamp, a second clamp, and 105 means connecting the clamps, and embracing the members, said second clamp having a curved surface adapted to engage the central support member and a flat surface adapted to engage the side support member, 110 said surfaces joining to form an apex, and a pivot located adjacent to the apex for connecting the clamp with said means, the curved surface being eccentric to the pivot, whereby the second clamp will be rocked 115 upon its pivot to bring the first mentioned clamp and the central and side support members into more intimate engagement when the side support member is moved into engagement with the flat surface of the second clamp. 120

4. In combination in a clamping device, a clamp, a second clamp, and means pivotally connecting the clamps, said second clamp having a curved surface, and a flat surface 125 joining the curved surface at an angle there-

to said means being pivotally connected with the second clamp adjacent to the juncture of the curved and flat surfaces, said flat surface being adapted to be engaged by a portion of the objects to be clamped together, whereby the curved surface will be brought into clamping engagement with the other object, and whereby the

clamping engagement of the first mentioned clamp with the objects will be increased. 10

In testimony whereof, I have hereunto subscribed my name this 4th day of September, 1915.

EDWARD O. KEATOR.
